UNITED STATES PATENT OFFICE.

EMIL MÜLLER, OF PFORZHEIM, GERMANY.

MACHINE FOR THE MANUFACTURE OF CHAIN MAIL.

Application filed August 26, 1921. Serial No. 495,726.

To all whom it may concern:

Be it known that I, EMIL MÜLLER, a citizen of the German Republic, residing at Pforzheim, Germany, have invented certain 5 new and useful Improvements in Machines for the Manufacture of Chain Mail, of which the following is a specification.

This invention relates to a machine for the manufacture of chain mail in which the 10 finished chain mail is alternately held suspended upon two groups of opposite holding organs displaced the one with regard to the other. The known machines of this 15 type work in such a manner that the chain mail hangs with its last row of rings upon the holders of one group and that each newly added ring is gripped by the holders of the opposite group which go up successively. In a machine of a known type the 20 corresponding holders of the first group of holders descend simultaneously when the holders of the opposite group ascend. The working method is similar to the knitting process as the rings are successively caught 25 by the holders of one group to be successively transferred to the holders of the opposite group.

With other machines all the holders of one group are lowered simultaneously when the 30 new row of meshes has been formed.

The fact that in the machines of both types the holding organs consist of single 35 frail holders which are driven individually is the reason that these holders are easily damaged wherefrom result irregularities in the formation of the chain mail.

This invention obviates this inconvenience by using combs whose teeth serve as ring 40 holders. The improved construction according to this invention presents the further advantage that the chain mail is not suspended by the last row of rings but by the last but one row of rings. The teeth and the comb are constructed in such a manner 45 that when the teeth get into the plane of the chain mail, that is to say into the plane in which the finished chain mail is suspended, the rings of the last row are placed vertically.

The advantages resulting from this 50 construction are obvious, the vertical position of the rings of the last row of rings enables the secure insertion of the new rings. The rings of the last row of rings are absolutely 55 free from the holders. The chain mail is absolutely at rest until the whole row of

rings is finished as the combs are stopped during the formation of the rings which is very favorable for the secure insertion of the individual ring meshes. 60

In order that the invention may be clearly understood, I shall proceed to describe the same with reference to the form of construction shown by way of example in the accompanying drawings, wherein the improved holder for the chain mail and its working method are illustrated in 4 figures.

Fig. 1 is an elevation.

Fig. 2 is a plan view.

Figs. 3 and 4 are detail views illustrating 70 the positions of the tools after the formation of a row of ring meshes.

a and *b* are the comb-shaped holders for the chain mail; *c* and *d* designate the teeth of the combs which have curved backs *m*. 75 Said teeth stand apart from one another at a distance which corresponds with the diameter of a ring. The teeth of the two combs are displaced, those of one comb with regard to those of the other comb, for a 80 distance which is equal to half the diameter of a ring.

As shown on Fig. 3 the rings of the last but one row of the finished chain mail hang upon the teeth *d* of the holder *b*. Fig. 4 85 shows the rings *f* of the last row of rings in vertical position bearing upon the back of the teeth *c* and supported by a shoulder of the comb *a*.

The formation of the ring meshes and the 90 insertion of the individual ring meshes *g* for the formation of a fresh row of rings is effected in the well known manner, the pieces of wire *g* having been bent previously to U-shape being inserted by a tool (pincers) 95 *k* into two adjacent ring meshes of the freely accessible last row of rings *f* to be closed to ring shape by a counter tool *i* (Figs. 2 and 3). After in this manner a complete row of interlocked rings has been 100 inserted the free mesh holder *a* is made to ascend in inclined direction so that its teeth *c* engage with the rings *f* of the previously 105 finished row of rings *f*, the recently inserted rings *g* being brought into the vertical position. The teeth of the holder *b* become thus free and the holder *b* is withdrawn from the plane in which the chain mail hangs (Fig. 4).

I claim:

1. An improved machine for the manufacture of chain mail of the type in which

the finished chain mail is alternately held suspended by two groups of opposite holders, comprising in combination elements for guiding the chain mail, two inwardly inclined reciprocating combs the one at the one side and the other at the opposite side of the chain mail, and upwardly directed teeth of said combs standing at distances apart which correspond with the diameter 10 of the rings of the chain mail.

2. In a machine for the manufacture of chain mail of the type described, two inwardly inclined reciprocating combs one at either side of the chain mail, and displaced 15 the one with regard to the other for an amount equal to half the diameter of the

rings of the chain mail, upwardly directed teeth of said combs having curved backs and standing at distances apart which correspond with the diameter of the rings of the 20 chain mail said teeth designed to engage with the rings of the last but one row of the finished chain mail the curved backs of the teeth bringing the rings of the last finished row of chain mail into the vertical position. 25

In testimony whereof I affix my signature in presence of two witnesses.

EMIL MÜLLER.
